AUTO LOCK

Victor L. Gilpin, Baltimore, Md., assignor to Gilpin Autolock Corporation, a corporation of Maryland

Application October 29, 1934, Serial No. 750,582

7 Claims. (Cl. 70—185)

This invention relates to improvements in locks, especially for automobiles and other motor vehicles and its objects are as follows:—

First, to make the locking bolt in the form of a screw, and to provide a locking lever by which to screw the bolt into locking and unlocking positions by turns in the proper direction.

Second, to provide a so-called adapter as the intermediary between the locking bolt and lever, said adapter being capable of being moved into a gripping position between said bolt and the hub of the locking lever by a turn of the key plug in the proper direction after a key has been inserted in the plug for the purpose.

Third, to combine a novel switch with the locking lever, or some other part turned thereby, for controlling the starter motor and ignition circuits.

Fourth, to provide a spring ejection for the key when the lock is finally locked, said ejection consisting of a simple mechanism embodied in the key plug and capable of operation by the key either with a gear or friction drive.

Other objects and advantages will appear in the following specification, reference being had to the accompanying drawing in which:

Figure 1 is a perspective view of the improved lock, the locking lever being shown in the unlocked position.

Figure 2 is a sectional view taken substantially on the line 2—2 of Figure 1.

Figure 3 is a cross section taken on the line 3—3 of Figure 2, the adapter being shown in the position in which it is left at the end of the half counter-clockwise turn of the locking lever for unlocking.

Figure 4 is a cross section taken substantially on the line 4—4 of Figure 2 but differing in the showing of the positions of the parts mainly to illustrate how the leaf tumbler re-engages the lock casing upon withdrawal of the key.

Figure 5 is a detail perspective view of the abutment end of the locking bolt.

Figure 6 is a detail perspective view of the plug cylinder, particularly illustrating the adapter.

Figure 7 is a diagrammatic view of the electrical switch, particularly illustrating the contactor cylinder in its various positions.

Figure 8 is a fractional diagram of the same switch, later described in detail.

Figure 9 is a detail sectional view of one end of the contactor cylinder.

Figure 10 is a detail sectional view mainly of

portions of the key plug and key, illustrating the spring-operated key ejector.

In carrying out the invention provision is made of a lock casing, generally designated 1, which comprises a hub 2 to receive the tubing 3 of the steering post 4, a bolt cylinder 5 and a bracket 6 which is securable to any convenient fixed support 7 by securing means 8. The tubing 3 has an opening 9 (Fig. 2) in permanent registration with the bore 10 of the cylinder 5. The steering post 4 has an opening 11 which is smaller than the opening 9 but coaxial with the bore 10 when the openings are in registration for locking.

A counterbore 12 in the cylinder 5 fixedly contains a hard metal filler 13 hereinafter known as the nut. This has an internal screw thread 14. The counterbore is longer than the nut, its extension 15 terminating in an annular bead 16. A set screw 17 carried by the cylinder 5, projects into the extension 15.

A bolt 18 is freely movable in the bore 10 of the cylinder 5 and in the bore of the nut 13. The two bores are continuous. The bolt has an external screw thread 19 which occupies the passage 14. This bolt is herein known as a screw bolt because of its having the external thread. Its movement is both axial and rotary, and as it moves axially it turns, thereby either locking or unlocking the steering post 4 with respect to the fixed bolt cylinder 5 providing that the openings 9, 11 are in registration as stated.

Actual locking is accomplished by a center plug 20. This enters the opening 11 when the screw bolt 18 is projected toward the steering post 4. The adjacent end of the screw plug is beveled at 21. This bevel reduces the possibility of the screw bolt being impeded by a slight non-registration of the opening 9 and bore 10. Under such a condition the opening 9 would expose an edge in the bore 10. If the full diameter of the screw bolt were carried out to the end it would be obstructed by said edge. The bevel 21 sets the diameter of the screw bolt back, so to speak, to the extent of the bevel and so avoids the foregoing possibility.

If the two openings 9, 11 are in axial registration the plug 20 will immediately enter the opening 11 upon a clockwise turn of the screw bolt 18 (looking at it from right to left). Should the openings be out of axial registration the center plug would be stopped but the screw bolt would make its full thrust nevertheless. A spring 22 then yields. Upon turning the steering post 4 a little in one direction or the other the center plug 55

will soon snap into the opening 11. The spring is contained by the screw bolt, and one end of the plug 20 is engaged by the spring.

That end of the screw bolt 18 opposite to the 5 bevel 21 has an abutment 23 (Fig. 5). This is in the nature of a segmental shell. The ends 24, 25 mark the limits of the abutment. An adapter or gripper, generally designated 26, is located within the confines of the abutment. One or the 10 other of the ends 24, 25 is engageable by the adapter at which time it occupies a gripping position which compels turning of the screw bolt when turning motion is applied to the adapter.

The adapter is of a shape substantially as illustrated in Figure 6. It consists of an elongated loop 27 which houses an eccentric pin 28. Motion of the pin in a circular path actuates the adapter. The loop 27 is formed with a strong lug 29 which, in itself, operates as a locking bolt. 20 It is the lug 29 which engages either abutment end and through said engagement causes turning of the screw bolt 18 when turning power is applied as stated.

The eccentric pin 28 is part of a key plug 30 25 (Fig. 2). The pin 28 is off-centered with respect to the key plug, hence is eccentric in its location. Turning of the key plug moves the eccentric pin 28 on its circular path so that the adapter 26 is moved across the end of the key plug. When 30 thus moved it slides in the slot 31 of a plug cylinder 32 which is fixed in the hub of the locking lever. The inner end of the plug cylinder extends up to the loop 27. The lug 29 projects outwardly from the loop (to the right) and occupies the slot 31. Turning of the plug cylinder, by means of the locking lever, therefore causes turning of the screw bolt 18 through the intermediary adapter 26, said adapter and the confronting parts of the shell 23 and cylinder 32 40 with which it coacts constituting a clutch mechanism.

Only one of several leaf tumblers 33 in the plug 30 is shown in the drawing (Figs. 2 and 4). The key plug 30 is of a known manufacture having no concern with the invention excepting insofar as the leaf tumbler is concerned. This tumbler is projectable from the key plug by spring action through holes 34 and 35 (Fig. 4) in the cylinder 32 and hub of the locking lever into 45 an opening 36 in the cylinder 5 of the lock casing. The key 37 has a formation 38 which, when it passes through the slotted aperture of the tumbler upon pushing the key in, displaces the tumbler inwardly into the confines of the plug 30 50 (Fig. 2) so that the locking lever hub is no longer locked against turning with respect to the lock casing. The plug has a key hole 39 (Figs. 2 and 10) into which the key is inserted preparatory to its being given a quarter turn in the clockwise 55 direction, this being the first act leading up to unlocking.

The hub, previously mentioned, is designated 40, this being the hub of the locking lever 41. This hub has a bore 42 and a counterbore 43. 60 The cylinder 32 is fixed, as previously indicated, in the counterbore 43, and its inner slotted end extends into the space afforded by the bore 42. The plug cylinder is prevented from coming out by a flanged lock ring 44 which is fixed in the 65 outer end of the counterbore 43. The bore 42 has a pair of diametrically opposite recesses 45, 46 (Fig. 3) into one or the other of which the lug 29 is projectable in order to key the bolt screw 18 and hub 40 together. The adapter 26 together 70 with the abutment ends 24, 25 and hub recesses 75

45, 46 comprises an intermediary structure between the locking lever and the bolt, causing motions of the bolt when the lever is shifted.

The hub 40 is, obviously, cylindrical, and it 5 turnably occupies the extension 15 as plainly shown. It has an annular recess near the outer end which contains the bead 16. The cylindrical part has an annular groove 47 into which the point 17 of the set screw extends so as to prevent the locking lever from being pulled away 10 from the bolt cylinder 5.

Close to the entrance of the key hole 39 in the key plug 30 there is a chamber 48 (Fig. 10). This contains a gear wheel 49 which is revoluble 15 on a shaft 50 fixed in the chamber. The opposite ends of a spring 51 are attached to the respective gear and shaft in such a manner that when the pinion is turned clockwise the spring will be wound up.

This winding is accomplished by the toothed 20 back 52 of the key 37. The teeth compose a rack, and the rack is formed on the other side of the key opposite to that having the formation 38. Upon the original insertion of the key the engagement of the rack with the gear turns the latter to wind up the spring. The spring will then be under sufficient tension to forcibly eject the key should the operator fail to give it the initial clockwise quarter turn in beginning to unlock, or to remove the key from the lock plug 30 when finally locking up.

When the key is given the foregoing initial turn a lug 53 (Fig. 10) on the key rides beyond a flange 54 on the lock ring 44 and so is prevented 35 from being ejected. The key remains in the lock as long as the mechanism is in an actual unlocked condition or is about to be put into that condition. In practice the foregoing gear drive can be substituted by a friction drive. In that case the gear 49 would be a friction wheel, and the rack 52 would be substituted by the more or less plain back of the key which, upon engaging the wheel would cause turning.

A novel switch is so combined with the automobile lock that its operation occurs simultaneously with locking and unlocking the steering post 4 as the locking lever 41 is swung for that purpose. The switch comprises a housing 55 which is secured to the bolt cylinder 5 in any proper way. It is preferably made of insulating material, and its mounting on the cylinder 5 includes an insulating shield 56. It has an internal space 57 (Fig. 3), the outer wall of which has pairs of contacts 58, 59 imbedded in it. The first pair is wired up in the starter motor circuit, for which purpose there are two terminals 60, 61 (Fig. 3). The second pair is wired up to the ignition circuit (Fig. 2), for which purpose there are two other terminals 62, 63.

A contactor 64, not necessarily of cylindrical form as shown, is adapted to move back and forth in the space 57 in a circular path as the locking lever 41 is swung. To this end the hub 40 of the locking lever carries a bracket 65 (Fig. 2) to which the shaft 66 of the contactor is fixed. The contactor is mounted on the shaft with somewhat of a tight fit, but is adapted to turn a little first to one side and then the other so that its contact strip 67 may either be in position to engage the pairs of contacts 58, 59 to close the respective circuits, or to disengage them thereby to open the circuits.

This turning of the contactor is accomplished automatically, and it involves the following struc- 75

ture:—The exposed end of the contactor has a lug 68 and a pin stop 69. A finger 70 is mounted on a pivot 71 adjacently to the stop 69. A spring 72, secured at one end to the pivot 71 and having its other end bent around that side of the finger remote from the stop 69, exercises pressure on the finger toward the stop so as to keep the finger and stop in engagement excepting one time (Fig. 8).

19. An enlargement 73 of the space 57 provides room for the finger 70. It is into this enlargement that two studs 74, 75 project. They are placed in radial directions with respect to the axis of the cylinder 5, but project into the enlargement 73 from opposite directions, the first being located on the outer wall, the second on the inner wall. The stud 75 is bevelled at 76.

The operation is readily understood. The leaf tumbler 33 (Fig. 4) is projected from the plug 20 30 by spring action when the key 37 is removed from the plug, and on the presumption that the opening 36 is in registration with the holes 34, 35 the leaf tumbler enters the opening and secures the locking lever hub 40 against turning 25 with respect to the fixed lock casing. Locking between 5 and 40 by means of the tumbler 33 occurs only when the key 37 is out of the lock. It is not possible to close the starter motor or ignition circuits while the key is out of the lock. Insertion of the key retracts the tumbler 33 when 30 reached by the formation 38. The spring 51 (Fig. 10) is wound up at the same time.

At the time of insertion of the key 37 the adapter 26 is in a neutral position, that is to say, 35 the lug 29 is free from each of the abutments 24, 25 (Fig. 5), and naturally free from the recesses 45, 46. The mere insertion of the key, as explained, releases the locking lever so that it could be swung to close the starter motor and 40 ignition circuits without unlocking the car, should that procedure be desired.

The immediate description is predicated on the mechanism being in the locked position, not as shown in Figures 1, 2 and 3 which illustrate the 45 unlocked position. The key 37 is inserted (repeating what has been stated already) and given a clockwise turn to the right. The eccentric pin 28 moves the adapter 26 out of its neutral position so that the lug 29 enters the recess 46 50 and engages the abutment end 25. The abutment 23 is then at the left of the diagonal center instead of at the right as at Figure 3.

Turn the locking lever 41 counter-clockwise from the upper center position (not shown) to 55 the lower center position (Figs. 1, 2 and 3). Remember that the lug 29 and hub 40 are locked together. The push of the lug is against the end 25. That end is part of the bolt screw 18. The push turns the screw counter-clockwise and 60 moves it away from the steering post 4 into the unlocked position. There is a slip connection between the lug 29 and the abutment 23 so that the axial motion of the bolt screw is provided for.

Upon desiring to relock the car it is necessary 65 to shift the lug 29 to the uppermost position in Figure 3. The lug must contact the end 24 so that a clockwise turn of the locking lever 41 in the direction of arrow 77 will impart a clockwise 70 turn to the bolt screw 18 and move it into the locking position. In order to shift the lug 29 the key is given a 180° turn in the clockwise direction. This reverses the position of the eccentric pin 28, and also of the lug 29 so that it engages the hub 75 recess 45. The foregoing clockwise turn in the

direction of arrow 77 restores the mechanism to the locked condition.

Consider the electrical switch. The contactor 64 is in the position *a* (Fig. 7) while the locking lever 41 is in the unlocking position (Fig. 1). The contactor is diametrically opposite to the locking lever. Upon turning the latter in the clockwise direction (arrow 77, Fig. 3) the contactor 64 will be turned in the counter-clockwise direction on its shaft 66 when the finger 70 engages the stud 74 as illustrated at position *b* (Fig. 7). Up to this time the contact strip 67 bridged the ignition contacts 59, but upon the counter-clockwise turn of the contactor 64 the strip was moved out of bridging position (position *b*), 10 15 thereby opening the ignition circuit.

Continued clockwise motion of the locking lever 41 brings the contactor 64 to position *c* (Fig. 7). The engagement of the lug 68 with the stud 75 turns the contactor clockwise until the lug clears the stud as shown at position *d*. During this clockwise turn the finger 70 is restored to its original radial position (position *d*) and remains there while the locking lever is moved the remaining distance (position *e*) and is later started on the return journey preparatory to unlocking the steering post.

Assume that the locking lever is in the locking position (diametrically opposite to the position in Figures 1 and 3). This shifts the adapter 26 to the original neutral position. The bolt 18 and hub 40 are not clutched together any longer.

The key 37 is given a final quarter turn clockwise. The lug 53 will then be in line with an opening 80 (Fig. 1) in the flange 54 at one side of the key hole 39. The lug 53 was passed through the opening 80 upon the original insertion of the key. The subsequent quarter and half turns moved the lug 53 farther away from the opening 80, and it is not until the final quarter turn in the same direction that the lug was again brought into registration with the opening, enabling the operator to withdraw the key.

Should he fail to do this the stored tension in the spring 51 will eject the key. The removal or ejection of the key permits the projection of the tumbler to the locking position (Fig. 4) so that the hub 40 is secured to the lock casing.

Revert to initially unlocking the mechanism. As this concerns the electrical switch, the contactor 64 is moved from position *e* to position *a*. The lug 68 passes under the stud 75 without the contactor 64 being affected, the bevel 76 insuring a free passage. As the finger 70 (position *f*, Fig. 8) passes the stud 74 it simply retracts against the tension of the spring 72 but immediately 55 springs back to the radial position *g* when the stud 74 is passed, and this without turning the contactor on its shaft 66.

It will be seen that when the contactor was last turned into the position *e* the contact strip 67 was placed into the proper position for engaging the contacts 58, 59. As these are passed the starter motor circuit is first closed and then the ignition circuit. The breach between the two sets of contacts is so small that the starting impulse will not be lost. Should the engine be stalled while driving in traffic the operator has only to press upon a button 18, (Fig. 3). This is known as the stall switch, and its contactor 79 65 will bridge the starter motor contacts 58 and start the engine again.

I claim:—

1. A lock comprising a nut having an internal screw thread passage, a bolt having a thread 75

- permanently occupying the passage and adapted to make endwise motions back and forth when turned with reference to the nut, a locking lever which is turnable on the axis of the bolt but in a fixed position with reference thereto so as to assume locking and unlocking positions, and an intermediary key-operated clutch mechanism between the lever and bolt transmitting the turning of the lever to the bolt, said mechanism having a slip connection with the bolt compensating for its endwise motions.
2. A lock comprising a nut having a screw thread, a bolt in permanently threaded connection with the nut and adapted to make endwise motions when turned with respect to the nut, a locking lever which is turnable on the axis of the bolt into locking and unlocking positions, an adapter which is turnable with said lever, and means by which the adapter is coupled to the bolt, said means having a slip engagement so as to maintain connection between the lever and bolt during endwise motions of the latter.
3. A lock comprising a nut having a screw thread, a bolt permanently screwed on the nut so as to make endwise motions into locking and unlocking positions when turned with reference to the nut, a locking lever turnable on the axis of the bolt to produce said motions, an adapter which acts as a gripper, means by which to shift the adapter to a gripping position, and means respectively on the bolt and locking lever providing a slip connection by which the adapter is coupled when in said position.
4. A lock comprising a screw bolt, a fixed nut in which the bolt is turnable to cause endwise motions into locking and unlocking positions, and manually turnable means having a slip connection with the bolt to produce said motions.

5. A lock comprising a screw bolt, a nut into which the bolt is threaded so as to make endwise motions into locking and unlocking positions when turned with respect to the nut, an abutment which is part of the bolt, an adapter which has a slip engagement with the abutment, a key plug which has an eccentric pin carrying the adapter, said plug being turnable and thereby to cause said engagement of the adapter, and a locking lever which is turnable on the axis 10 of the bolt, with which lever said adapter is interlocked by said turning of the plug so that turning of the lever is imparted to the bolt.

6. In a lock, a screw bolt having a segmental shell providing an abutment, said abutment having abuttable ends, a key plug in line with the bolt and having an eccentric pin on its end next to the bolt, a plug cylinder turnably containing the plug and having a slotted extension, a locking lever hub fixedly carrying said cylinder and having a recess, and an adapter guided in the slotted extension, said adapter comprising a yoke containing the eccentric pin and a lug engaging at least one of the abuttable ends and entering said recess upon turning the key plug. 25

7. In a lock, a screw bolt having a segmental shell comprising an abutment having abuttable ends, a turnable key plug having an eccentric pin, a locking lever having a hub with diametrically opposite recesses, said lever being turnable to turn the screw bolt, and an adapter which is movable to an operative position by turning the key plug in one direction, said adapter having a yoke in which the eccentric pin works, and a lug simultaneously engaging one of the ends and one of the recesses. 30 35
